UNITED STATES PATENT OFFICE.

VICTOR M. SUMMA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

MONOSILL CAR-UNDERFRAME.

1,066,546.

Specification of Letters Patent.

Patented July 8, 1913.

Application filed December 2, 1911. Serial No. 663,653.

To all whom it may concern:

Be it known that I, VICTOR M. SUMMA, residing at St. Louis, Missouri, and being a citizen of the United States, have invented 5 certain new and useful Improvements in Monosill Car - Underframes, of which the following is a full, clear, and exact description, such as will enable others skilled in the art to which it appertains to make and to use 10 the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings: Figure 1 is a transverse section through the car equipped with the 20 present invention. Fig. 2 is a fragmentary plan view of an improved underframe hereinafter described. Fig. 3 is a longitudinal sectional view taken on the plane of line 3—3 of Fig. 2. Fig. 4 is a similar view 25 taken on the section 4—4.

The object of the invention is to provide a car underframe equipped with a single center sill of sufficient strength to carry the entire weight of the car and its load, and to 30 provide cross bearers coöoperating with said single center sill, which cross bearers shall be properly supported from the center sill and project thereabove, as shown in the drawings and be suitably stiffened so that 35 the load may be carried entirely on the center sill.

Another object is to so position these cross bearers with reference to the center sill that the tops of the cross bearers shall project 40 above the plane of the center sill and serve as stops for longitudinally extending nailing strips which are supported by said cross bearers and are nested under outstanding flange of the cross bearers at one end as 45 shown particularly in Figs. 3 and 4.

Referring specifically to the parts, F is the center sill, which may be of any preferred form, though it is shown as comprising a 50 rolled I section with wide top and bottom horizontal flange and with vertical web. The bottom flange H and the top flange G may, within the spirit of this invention, comprise separately formed angles or other commercial forms of metal riveted to the

vertical web, but it is preferred that a single 55 rolled section as shown shall be used.

Extending transversely of the underframe and above the top of the center sill is a single rolled channel member I which is connected through its bottom flange with the 60 center sill by means of connecting plates B B and is provided with a recess S in its lower part for the reception of the upper portion of the single center sill, as best shown in Fig. 1.

Referring specifically to the cross bearer channel it will be noted that the top flange 1 is continuous from end to end, while the bottom flange 2 is intermittent at the recess S above referred to. The portion 3 of the 70 web of said channel is flanged laterally outward from the major portion of the vertical web thereof, as best shown in Figs. 2 and 4, and this laterally extended flange is secured by rivets 4 directly to the top flange of the 75 center sill.

The connecting plates B B may be of triangular shape as shown and are provided with flanges 5 through which flanges extend rivets 6 for joining said connection plates 80 with the web of the center sill. As best shown in Fig. 1 the connection plates B B extend laterally some distance beyond the edges of the recess S and are connected through horizontal flanges 7 directly with 85 the lower flange 2 of the channel shaped cross bearer so that said cross bearer is connected by its web to the top flange of the center sill and by its bottom angles through the connection plates B B with web of said 90 center sill, thus producing a structure of proper stiffness for use in a car of this type.

Secured directly to the webs of the channel cross bearers I are brackets 10 of angle shape, upon which rest the wood nailing strips 11, to which wood nailing strips the 95 floor 12 of the car is secured.

As will be seen in Figs. 3 and 4, the nailing strips project at one end under the top flange 1 of the cross bearers I, and are preferably secured in position by through bolts 13.

Any form of side sill may be used with the cross bearer construction described, though for convenience of illustration I have 105 shown the Z sections 15.

What I claim is—

1. In a car underframe, the combination,

- with a center sill, of a continuous rolled channel cross bearer having a bent portion cut from the lower part of the web to form a recess to accommodate part of said sill, 5 said portion constituting an outwardly extending flange integral with said cross bearer and engaging the top of said sill.
2. In a car underframe, the combination with a center sill, of a continuous rolled metal cross bearer straddling said sill and having an outwardly extending flange integral with said bearer, conforming to the width of, and resting on the top of said sill.
3. In a car underframe, the combination comprising a single center sill provided with relatively vertical web, of a cross bearer consisting of a single continuous rolled and flanged member cut away to form 20 a sill receiving recess wider than the thickness of said sill and flanged connecting plates secured directly to said cross bearer and to the web of said center sill bridging said recess.
4. In a car underframe, the combination comprising a single center sill provided with relatively vertical web and horizontal top flange, of a continuous cross-bearer recessed to accommodate the top flange of said sill, 30 an integral flange extending laterally from the web of the cross bearer and connected to the flange of the sill and connection plates disposed in a plane parallel to the cross-bearer and secured directly to the cross beam and to the web of the center sill.
5. In a car underframe, the combination comprising a single center sill provided with relatively vertical web and horizontal top flange, of a continuous rolled channel shaped 40 cross bearer recessed for said sill, a flange extending laterally from the web of the cross bearer and connected to the flange of the sill and connection plates secured directly to the bottom flanges of the cross 45 bearer and to the web of the center sill, said connection plates completing the bottom flange of the cross bearer to the sill.
6. In a car underframe, the combination comprising a single center sill provided 50 with relatively vertical web and horizontal top flange, of a recessed cross bearer the recess of which receives the upper part of said sill whereby the cross bearer extends above, and laps the side of the sill, and bracing 55 means connecting the web of the cross bearer to the flange of the sill and additional bracing means extending from a flange of the cross bearer to the web of the sill.
7. In a car underframe, the combination comprising a single center sill provided 60 with relatively vertical web and horizontal top flange, of a cross bearer formed from a single rolled channel recessed to receive the upper portion of said sill and the web of 65 the cross-bearer lapping the top flange of the sill.
8. In a car underframe, the combination comprising a single center sill provided with relatively vertical web and horizontal top flange, of a cross bearer formed from a continuous flanged channel member having a recess formed in its lower portion, a single flange outlining the top of said recess and riveted directly to the flange of said sill. 70
9. In a car underframe, a flanged cross bearer having a continuous top flange, a sill recess being formed in the lower part of the web of said cross bearer, and the bottom flange of the cross-bearer being intermittent by said recess, a center sill disposed in said recess and projecting below said cross-bearer, and connecting plates occupying the angles between the projecting part of said center sill and said bottom flange. 75
10. In a car underframe, the combination comprising a single center sill provided with relatively deep vertical web and horizontal top flange, of a relatively shallow 90 channel shaped cross bearer recessed in its lower part to accommodate said top flange, said cross bearer resting on the flange of said sill and lapping its web portion, and brackets secured to said sill below said cross 95 bearer; said brackets substantially closing the recess in the cross bearer.
11. In a car underframe, the combination comprising a single center sill provided with relatively vertical web and horizontal top flange, of a pair of laterally extending 100 brackets secured to the web of said sill, a recessed channel cross bearer resting on said brackets and connected to the flange of said sill, and nailing strips supported by said 105 cross bearers and extending below and fastened to the top flanges thereof.
12. In a monosill car underframe, the combination with a single I section center sill having substantially vertical web and laterally extending top and bottom flanges, 110 of a cross bearer member extending across said center sill having cut away portions forming a recess of the width of said top flange adapted to receive said center sill, and 115 reinforcing means fixed to said cross bearer member at opposite sides of said recess and each being fixed by a common fastening means to the web of said center sill below said cross bearer. 120
13. In a monosill car underframe, the combination with a single I section center sill having substantially vertical web and laterally extending top and bottom flanges, 125 of a channel section cross bearer having continuous straight upper flange and having its lower flange cut away to receive the top flange of the center sill, said cutaway portion being of the width of said top flange.
14. In a monosill car underframe, the 130

- combination with a single I section center sill having substantially vertical web and laterally extending top and bottom flanges, of a channel section cross bearer having continuous straight upper flange and discontinuous parallel lower flange and having its web cut away to admit the center sill through said lower flange.
15. In a monosill car underframe, the combination with a single I section center sill having substantially vertical web and laterally extending top and bottom flanges, of a channel section cross bearer having continuous straight upper flange and discontinuous parallel lower flange and having its web cut away to admit the center sill through said lower flange, and angle plates forming a continuation of and connecting the portions of said lower flange to the web of said center sill, and rivets connecting said angle plates to the web of the sill and to each other.
16. In a monosill car underframe, the combination with a single I section center sill having substantially vertical web and laterally extending top and bottom flanges, of a channel section cross bearer having continuous straight upper flange spaced from the web of said sill and discontinuous parallel lower flange and having its web cut away to admit the center sill through said lower flange, and angle brackets connecting the portions of said lower flange to the web of said sill.
- 35 17. In a monosill car underframe the combination with a single I section center sill having substantially vertical web and laterally extending top and bottom flanges, of a channel section cross bearer extending above said center sill having cut away portions forming a recess adapted to receive
- 50 said center sill and having part of its web overlapping the upper flange of said center sill, and angle brackets extending from and connecting the bearer on opposite sides of 45. said recess to the web of said center sill.
18. In a monosill car underframe the combination of a single center sill in the form of an I-beam and a cross bearer of rolled metal having a recess in the underside thereof, adapted to receive said center sill, integral means co-extensive with the width of the top flange of the sill for attaching the web of said cross-bearer to said top flange, said recess being of a width adapted to contain the upper flange of said center sill whereby the top of the cross-bearer may be positioned at different vertical distances from the center sill by deepening the recess.
- 55 19. In a monosill car underframe the combination of a single center sill in the form of an I-beam and a cross-bearer of sheet metal having a recess in the underside thereof adapted to receive said center sill, integral means co-extensive with the width of 60 the top flange of the sill for attaching the web of said cross-bearer to said top flange, said recess being of a width adapted to straddle the upper flange of said center sill to position the top of the cross-bearer at 70 different vertical distances from the center sill, and vertically disposed connecting plates extending from the webs of said sills to said cross-bearer and outlining the lower 75 side of said recess.

In witness whereof I have hereunto set my hand in the presence of two witnesses.

VICTOR M. SUMMA.
